UNITED STATES PATENT OFFICE

EDWIN BURKE, OF MANILA, PHILIPPINE ISLANDS

MEANS AND METHOD FOR REMOVING DETACHABLE MOLD SIDES

Application filed September 24, 1928. Serial No. 307,913.

The invention relates generally to the molding of plastic substances into large blocks, and it has specific relation to soap casting or molding. In molding soap into 5 large blocks from which to later form cakes, etc., it is customary to use soap frames or molds having separable walls to permit removal from the molded block, it being the usual procedure to first remove the mold 10 sides and then the ends but due to the greater area of the sides of the soap frames, great difficulty has been encountered in removing the mold sides quickly and without impairing the faces of the block with which they 15 contact, due to sticking of said faces to said sides. While this trouble has given rise to numerous efforts toward overcoming the difficulty, the trade to-day lacks a practicable and 20 successful way of quickly and easily removing the mold sides without injuring the molded block. It is therefore the aim of my invention to fulfill this need.

With the foregoing in view, the invention resides in the novel subject matter herein- 25 after described and claimed, the description being supplemented by the accompanying drawings in which:—

Fig. 1 is an end elevation partly broken away and in section showing one common 30 form of soap frame or mold, illustrating the improved side remover in readiness for operation.

Fig. 2 is a vertical longitudinal section substantially on line 2—2 of Fig. 1.

Fig. 3 is a view similar to Fig. 1 but illustrating the manner in which the mold side is moved upwardly and outwardly from the 35 molded block.

Fig. 4 is a top plan view.

Fig. 5 is a detail longitudinal section on line 5—5 of Fig. 4.

Fig. 6 is a detail transverse section on line 6—6 of Fig. 5.

40 Figs. 7 and 8 are detail elevations partly in section showing different features of construction which may be used at the lower ends of the pull rods hereinafter described.

Fig. 9 is a fragmentary side elevation illustrating the manner in which the pull rods 45

may be connected with the mold side in some instances.

Fig. 10 is a side elevation showing still further provision for connecting the pull rods with the mold sides.

55

A soap frame or mold M is shown mounted upon the usual truck T, said mold embodying a bottom B, ends E and sides S, together with means for clamping these parts in assembled relation and for permitting separation of the 60 sides and ends from each other and from the bottom when the mold is to be removed from the molded block of soap. In some instances, bolts are passed through openings O in the ends of the sides S, and in other 65 constructions, other means are provided for holding the mold sections assembled. The outer sides of the side walls of some forms of molds are plain, while the corresponding sides of other kinds of molds are provided 70 with reinforcements, for instance, channel metal reinforcements R (Fig. 10). These different characteristics of different molds are merely mentioned in order that certain 75 aspects of the present invention may be more fully explained. In giving this explanation, specific reference will be made to the details of construction selected for illustration in the present application, but it is to be understood at the outset that the invention is not 80 restricted to this particular disclosure.

A bar 12 is provided to rest slidably upon the mold ends E, said bar preferably consisting of a wooden core 13 and angle metal bars 14 covering the same. Transverse thrust bars 85 15 preferably of angular form in transverse section, are riveted or otherwise secured to the lower side of the bars 12, these thrust bars being of a length for reception between the upper portions of the mold sides S.

The ends of the bar 12 are formed with longitudinal slots 16 and pull rods 17 have their upper ends passed slidably through said slots. These rods are adapted for disposition 90 at the outer sides of the mold ends E and they are provided at their lower ends with means for connecting them with the lower portions of the sides S. In a number of the views, hooks 18 are shown on the lower ends of the rods 17 for engagement with certain of the 95 100 rods 17 for engagement with certain of the

openings O or with projections 19 secured to the sides S. In other views, eyes 20 are shown on the lower ends of the pull rods 17. These eyes may be passed over projections such as 19, or they may receive the ends of a length of rod or pipe 21 passed longitudinally through one of the reinforces R, the latter being shown in Fig. 10. Preferably, the hooks 18 or eyes 20, as the case may be, are threaded into sockets such as 22 (Figs. 7, 8) in the lower ends of the rods 17. This permits interchange of hooks or eyes if advisable and also permits a damaged hook or eye to be removed and replaced with another.

The upper portions of the rods 17 are threaded and upon them, nuts 23 are provided, each nut being preferably equipped with oppositely projecting hand grips 24. A washer 25 may well be interposed between each nut 23 and the bar 12.

The mold side remover comprising the parts 12—17—23—15—18 or 20, etc., is applied to the mold as shown for instance in Figs. 1, 2, 3, 4 and 10. The bar 12 is placed upon the ends E and the lower ends of the rods 17 are connected with one of the sides S. The nuts 23 are then tightened and this not only causes upwardly sliding of the side S, but effects sliding of the bar 12 laterally so that the thrust bars 15 force the upper portion of the side S laterally outward as shown in Fig. 3. During tightening of the nuts 23, the lengths of rods 17 between the lower ends of these rods and the bar 12, are contracted and as such contraction takes place, the rods have a tendency to swing into a plane parallel with the side S, instead of remaining at an acute angle to this side. This tendency of the rods causes the bar 12 to slide upon the ends E and during this movement, the thrust bars 15 laterally force the upper end of the side S outwardly. By thus sliding this side in an edgewise direction and simultaneously moving it laterally outward, it is quickly and easily separated from the molded block of soap and the latter is left intact instead of being severely mutilated as is common under the old practice. After removal of one side S, the rods 17 are disconnected from this side and connected with the opposite side, and the same procedure is then carried out with the latter. During the removal of either side S, if the entire block of soap has a tendency to shift upwardly with said side, this may be prevented by placing plates or blocks 26 under the bars 15 upon the molded block. After removal of the mold sides, the ends may be separated from the molded block by cutting with the usual wires or in any other manner. By providing the longitudinal slots 16 in the bar of member 12, the pull rods 17 may be adjusted toward or from each other to accommodate soap frames or molds of different lengths.

It will be seen from the above that not only have I produced a unique and advantageous

mechanical contrivance for removing mold sides without injuring either them or the molded contents, but that my invention also involves the novel method of sliding a mold side in an edgewise direction and outwardly forcing such side while it is being so slid. This sliding movement together with the simultaneous lateral thrust causes the adhesion between the soap block and the side of the frame or mold to be quickly broken by comparatively few turns of the hand nuts 23 and when once this adhesion is broken, the side of the soap frame may be quickly removed. In actual practice, with this device, I have removed the sides of a soap frame in less than one minute whereas under the old practice, it frequently requires two men fifteen minutes or more to remove one side of the frame. Pulling or forcing the sides in only a lateral direction as in the old practice frequently results in both the soap block and the frame side being damaged and also in a portion of the soap block adjacent the center of the side adhering to the latter and pulling out of the remainder of the block since the center of the soap block is the last part of it to harden. This occurs frequently when the soap has not been permitted to stand in the frame or mold a sufficient length of time to permit it to harden clear to the center of the block. If the side of the frame is removed by merely an edgewise sliding movement, it must be slid to a considerable extent before the adhesion between the soap block and side can be reduced sufficiently to permit the side to be pulled laterally by hand away from soap block, but by simultaneously thrusting the top of the side laterally and sliding it edgewise, the adhesion is quickly broken with no injury to either the soap block or the frame side.

I claim:

1. In a removing means for a detachable mold side; means for sliding said side edgewise, and means for moving said side outwardly in a direction transverse to its direction of sliding movement.

2. In a removing means for a detachable mold side; means for sliding said side edgewise, and means for outwardly moving said side in a direction transverse to its direction of sliding, both of said means having common actuating means.

3. In a removing means for a detachable mold side; a thrust member for disposition on the mold to thrust laterally outward upon said side, and longitudinally contractible pulling means for disposition at an acute angle to said detachable side, said pulling means being connected with said thrust member and having means for connection with said detachable mold side to simultaneously slide said side edgewise and move said thrust member to outwardly thrust said side.

4. In a removing means for a detachable

5 mold side; a thrust member for slidable engagement with the mold in position to slide laterally outward and thrust against said detachable side, and longitudinally contractible pulling means connected with said thrust member and having means for connection with said detachable side, said pulling means being adapted for disposition at an acute angle to said side and at an acute angle to the line of movement of said thrust member, whereby upon contraction of said pulling means, edgewise sliding of said side and outward sliding of said thrust member to outwardly force said side will be effected.

10 5. In a removing means for a detachable mold side; a thrust member for disposition on the mold to thrust laterally outward upon said side, said thrust member having an opening for inward spacing from the plane of said side, a pull rod passing slidably through said opening and adapted for disposition at an acute angle to said mold side, said pull rod having means for connection with said side, and a nut threaded on said rod and abutting said thrust member, tightening of said nut serving to slide said side and to move said thrust member to force said side laterally outward.

15 6. In a removing means for a detachable mold side; a thrust member for slidable engagement with the mold in position to slide laterally outward and thrust upon said detachable side, said thrust member having an opening, a pull rod passing slidably through said opening and adapted for disposition at an acute angle to said detachable side and at an acute angle to the direction of movement of said thrust member, said pull rod having means for connection with said side, and a nut threaded on said rod and abutting said thrust member, tightening of said nut serving to slide said side and to slide said thrust member to force laterally outward on said side.

20 7. In a removing means for a detachable mold side; a bar to rest slidably on the ends of the mold, transverse thrust bars secured to said bar to outwardly thrust upon said detachable side, and longitudinally contractible pull members connected to the ends of said bar and adapted for positioning at the outer sides of said ends of the mold, said pull members having means for connecting them to the detachable mold side in acute angular relation with the latter.

25 8. In a removing means for a detachable mold side; a bar to rest slidably on the ends of the mold, the ends of said bar having openings, transverse thrust bars secured to the first named bar to outwardly thrust upon said detachable side, pull rods passing slidably through said openings and adapted for disposition at the outer sides of said ends of the mold, said rods having means for connecting them with said mold side, and nuts

threaded on said rods and abutting said first named bar.

9. A method of removing a detachable mold side from mold contents which adhere to said side, comprising the steps of sliding the side in an edgewise direction and while so sliding said side, moving it laterally outward.

10. In a method of removing a detachable mold side from mold contents which adhere to said side, the step of simultaneously sliding edgewise and thrusting outwardly the said side until the adhesion is broken.

In testimony whereof I affix my signature.
EDWIN BURKE.
